CLAIM

The ornamental design for a hearing aid as shown and described.

DESCRIPTION

FIG. 1 is a top and left side perspective view of a hearing aid showing our new design;

FIG. 2 is a bottom and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is a top and left side perspective view showing the hearing aid in a pair; and,

FIG. 11 is a bottom and right side perspective view showing the hearing aid in the pair.

The broken lines in the drawings depict portions of the hearing aid which form no part of the claimed design.

The broken lines in FIGS. 10 and 11 which depict a symmetrical hearing aid in the pair also form no part of the claimed design.

The long dash-short dash broken lines in FIGS. 1 and 9 define the bounds of the enlargement and form no part of the claimed design.
